UNITED STATES PATENT OFFICE

RICHARD C. COUPLAND, OF THE UNITED STATES ARMY, NORFOLK, VIRGINIA

SYNCHRONIZED CONTROL SYSTEM FOR MACHINE GUNS

Original application filed August 1, 1927, Serial No. 209,893. Divided and this application filed November 6, 1928. Serial No. 317,553.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a synchronized control system for machine guns which will permit the gun to be fired between the blades of a rotating propeller and is a division of copending application, Serial 209,893, filed

10 August 1, 1927.

The principal object of the invention is to provide a compact impulse generator for a gun control assembly which provides for the interchangeable attachment of a mechanical 15 or electrical control.

The invention further aims to provide an electrical control, including an electrically actuated plunger in which complete adjustment of the plunger may be had.

20 With the foregoing and other objects in view, the invention resides in the novel arrangement and combination of parts and in the details of construction hereinafter described and claimed, it being understood that 25 changes in the precise embodiment of the invention herein disclosed may be made within the scope of what is claimed without departing from the spirit of the invention.

A practical embodiment of the invention 30 is illustrated in the accompanying drawing, wherein:

Fig. 1 is a longitudinal, sectional view of a gun control assembly showing an application of a mechanical control unit for the 35 pulse generator;

Fig. 2 is a similar view, showing an application of an electrical unit.

Referring to the drawing by characters of reference:

40 There is shown in Fig. 1 a gun control assembly which consists of an impulse generator A controlled by an operating mechanism B and connected to a trigger motor C by means of an impulse cable and cable housing D.

The impulse generator unit is arranged to constitute a compact integral part of the engine synchronized during or after assembly thereof and consists of a housing 5 in which 50 is mounted a driving shaft 6, receiving its

energy from the engine and rotating at a speed to give a cam impulse for each blade of the propeller. The shaft carries a cam 7 arranged to engage the foot 8 of a cam follower 9 which is parallel to the cam shaft. Threaded in the head of the follower is a plug 10 in which is secured the impulse cable 11 leading to the trigger motor C and sheathed in a suitable tube 12.

55 The operating mechanism for controlling the cam follower 9 comprises a spring-pressed plunger 13 disposed in the housing 5 above the cam shaft and arranged to enter a recess 14 in the follower for the purpose of holding the follower in inoperative position clear of the cam 7. When this condition obtains, the trigger motor is inactive and the trigger 15 will be held by the cam 16 in the inward position, as shown in Fig. 2 where it is unavailable to actuate the sear 70 slide 17 of the gun.

60 The withdrawal and retention of the plunger 13 is accomplished by means of a cable 18 which is secured to a hand lever 19. The socket member 20 in which the 65 sheath 21 on the cable 18 is anchored is threaded as at 22 to the housing 5 and establishes a seat for the plunger spring 23 which forces the plunger into the recess 14 of the follower.

65 In Fig. 2 an electrical control unit for the impulse generator interchangeability replaces the mechanical control unit of Fig. 1. This unit consists of a casing 24, having a threaded neck 25 for attachment to the housing 5 and inclosing a coil 26 which when energized retracts a plunger 27 from engagement with the cam follower 9. Adjustment of the plunger is provided by threading the plunger head 28 on the stem 29 of the plunger 90 and also by a lock nut 30 on the stem which confines a plunger spring 31 seated in the hollow neck 25 of the casing.

80 The coil is energized by a suitable source of electrical current, not shown, through any 95 desired circuit closing means, such as, for example, the contact button 32 which, when compressed, engages the contacts 33 and completes the circuit in a well-known manner. The button illustrated is of the thumb oper- 100

ated type to be used on an airplane control stick, there being two buttons mounted side by side for the respective control of a right or left hand gun.

5 I claim:

1. An impulse generator for synchronizing gear, including a housing having means for the interchangeable attachment of either mechanical or electrical control.
- 10 2. An impulse generator embodying an impulse transmitting member and a plunger for holding said member inoperative including means for adjusting said plunger.

RICHARD C. COUPLAND.
